SECTIONALIZED ZERO SETTING MEANS

John Lydfors and Sven Axel Evert Lundin, Malmö, Sweden, assignors to Aktiebolaget Addo, Malmö, Sweden, a corporation of Sweden

Application July 7, 1947, Serial No. 759,346
In Sweden July 12, 1946

5 Claims. (Cl. 235—144)

1

In calculating machines of the Odhner type it is often desired to have the possibility of zero setting the revolutions counting or multiplier register without zero setting the result or product register at the same time, and consequently there is generally used a special zero setting device for each of these two counting registers. However, when it is desired to zero set both counting registers it is too complicated to actuate two different zero setting devices for which reason efforts have been made optionally to zero set either of or both counting registers by means of a single operating means. These efforts have however led to constructions presenting various disadvantages such as being difficult to operate, requiring a great space and being expensive.

A principal object of the present invention is to provide a zero setting device of the type in question, which does not present the disadvantages outlined above.

Another object of the invention is to provide a zero setting device for optionally zero setting certain digit wheel groups in one and the same counting register or in several co-ordinated counting registers for any purpose. Such a digit wheel group may of course consist of one or more digit wheels.

Further objects and advantages of the invention will appear from the following detailed description of an embodiment of the invention shown in the annexed drawings as an example only. As it is of special advantage to use the invention for zero setting the revolutions and result counting registers in a calculating machine of the Odhner type, the application of the invention to such a machine has been chosen as an example. This example is merely illustrative and must not be considered as limiting the invention in any respect whatever.

In the drawings:

Fig. 1 is a front view of a part of a counting register carriage of an Odhner calculating machine, in which parts irrelevant to the invention and a portion of the device according to the invention have been omitted for the sake of clearness.

Fig. 2 is a section along the line II—II in Fig. 1.

Fig. 3 is a perspective view of a zero setting device for the revolutions counting register to the left in Fig. 1.

Fig. 4 on a greater scale shows a mechanism for zero setting the result counting register to the right in Fig. 1, as seen from the right in relation to the last-mentioned figure, the parts being shown in the operative position, i. e. the position in which the result counting register is zero set.

2

Fig. 5 shows the same mechanism as Fig. 4 with the parts in inoperative position, in which no zero setting of the result counting register takes place.

Fig. 6 is a view similar to Figs. 4 and 5, certain parts being broken away for the sake of clearness, and shows the position of the parts just before the completion of a zero setting operation.

Fig. 7 shows a part of the zero setting mechanism for the result counting register, seen from above, the parts occupying the same position as in Fig. 4.

Fig. 8 in a corresponding manner shows certain parts of the zero setting device in the position they occupy in Fig. 5.

Fig. 9 to 12 are perspective views of different positions of certain parts of the zero setting mechanism for the result counting register during a zero setting operation.

Figure 13 represents a structure substantially corresponding to that of Figure 1, with the exception that two adjustable cam mechanisms are used instead of one as shown in Figure 1.

The calculating machine in which the device according to the invention is supposed to be mounted has a counting register carriage with a frame 1 in which there is mounted a zero setting shaft 2 common to a revolutions counting register A and a result counting register B. For rotation of the shaft 2 there is further mounted in the frame 1 a shaft 3 with a crank handle 4 and a gear segment 5. This gear segment meshes with a gear 6 which is freely rotatable and displaceable on the shaft 2 and has the face of its hub helically formed, while the helical end of the hub is pressed by a spring 7 against a correspondingly shaped ring 8 fixed to the shaft 2. The hub end of the gear 6, the spring 7 and the ring 8 form a one-cycle clutch. This clutch arrangement is such that when the gear segment 5 is rotated counter-clockwise with regard to Figure 2 to cause shaft 2 to perform a single rotation in clockwise direction, a spring 9 will be able to return gear segment 5 to its normal position shown in Fig. 2 without rotation of the shaft 2. On the hub portion of the gear segment 5 there are some projections 10 cooperating with a latch pawl 12 actuated by a spring 11, in such a way that the gear segment 5 cannot return to the normal position until the gear 6 and thus the shaft 2 has been rotated a full revolution.

In the revolutions counting register A a number of digit wheels 13 (only one is shown) are freely rotatably mounted on the shaft 2, and for zero setting the digit wheels, there is arranged a bar 15 known per se which is provided with projections 14 and is displaceable in the longitu-

dinal direction in a longitudinal groove provided in the shaft 2. At the left end of the shaft 2 (Figs. 1 and 3), the bar 15 is provided with a radially extending arm 16 which by a spring (not shown) is held applied against the face of a cam ring 17 which is coaxial with the shaft 2. The active face of the annular cam 17 is situated in a plane at right angles to the axis of the ring except on one place where there is a recess 18 having a steep wall and an inclined wall. Normally the arm 16 of the bar 15 rests in this recess. When the handle 4 is operated for zero setting and the shaft 2 is thus rotated one revolution in the clockwise direction in relation to Fig. 3 the arm 16 of the bar 15 slides up along the inclined side wall of the recess 18 while moving the bar 15 against the action of a spring not shown. During the rotation of the shaft 2, each projection 14 engages a zero setting tooth (not shown) on the corresponding digit wheel 13, so that the digit wheels are returned to zero in the known manner. When the shaft 2 has completed one revolution, the spring (not shown) presses the arm 16 of the bar 15 down into the recess 18, so that the projections 14 are moved out of the way and the digit wheels 13 may freely rotate under the action of the machine impulses supplied to them during the calculating operation.

Inasmuch as, in an Odnher machine, it is always desired to return the revolutions counting register to zero each time a zero setting is to take place, the cam 17 is stationarily arranged in relation to the shaft 2, so that the revolutions counting register is returned to zero each time the shaft 2 is rotated by means of the handle 4.

The result counting or product register B has also a number of digit wheels 19 (only one is shown) which may be zero set by means of a bar 20 carrying projections 20a. This bar is inserted in the shaft 2 so as to be displaceable in longitudinal direction. The bar 20 is movable by means of an annular cam 21 (to be described later) in principally the same manner as the projection bar 15 in the revolutions counting register A. Since, however, in Odnher machines it is sometimes desired to have the possibility of zero setting the revolutions counting register A without zero setting the result counting register B, the annular cam 21 is displaceable from the operative position to an inoperative position in a manner to be described in detail later.

As is evident from Figs. 4 and 5, the annular cam 21 is provided with a bottom 21a by means of which it is fixed to an arm 22 of a lever rotatable about an axis 23. Besides the arm 22, this lever has an upwardly extending arm 24 to which one end of a tension spring 25 is fixed, the other end of which is fixed to the frame 1. The spring 25 urges the lever 22, 24 into and tends to hold the same in the position shown in Figure 4, in which the annular cam 21 is eccentrically situated in front of the right end of the shaft 2 (Fig. 1). In this position the cam 21, as will be described later, is active and zero sets the digit wheels 19 in the result counting register upon rotation of the shaft 2.

However, when it is desired that the digit wheels 19 of the result counting register B shall not be zero set upon rotation of the shaft 2 by means of the handle 4, the lever 22, 24 is moved by means of a handle 26 against the thrust of the spring 25 into the inoperative position shown in Figure 5, in which the annular cam 21 is coaxial with the shaft 2. The handle 26 is fixed to the lever arm 22 and projects through an opening in the hous-

ing 27 of the counting register carriage. The lever 22, 24 is maintained in its Figure 5 position against the thrust of the spring 25 due to the fact that the lever has a rearwardly extending arm 28, at its rear end bent to a lug which in the operative position of the cam 21 (Fig. 4) is situated under a latch or pawl 30 actuated by means of a spring 29. When the lever 22, 24, 28 is moved to the position shown in Fig. 5, the pawl 30 is moved out of the way by the lug of the arm 28 against the thrust of the spring 29. The pawl snaps in under the lug and locks the lever 22, 24, 28 in adjusted position. In order that the cam 21 may be returned to its operative position after a single rotation of the shaft 2, the latch or pawl 30 is provided with a cam surface 30a cooperating with a radially extending arm 31. This arm is arranged at the right end (Fig. 1) of the projection bar 20 and occupies the normal position shown in Figs. 4 and 5 under the cam surface 30a. At the end of a single rotation of the shaft 2 in the clockwise direction, the arm 31 meets the cam surface 30a and swings the latch or pawl 30 away from the lug of the lever arm 28, so that the lever 22, 24, 28 can return to the position shown in Fig. 4 under the action of the spring 25. This releasing operation is shown in Fig. 6 where the projection bar arm 31 is just about to leave the cam surface 30a on the latch or pawl 30. As the projection bar arm 31 just at the end of the rotation of the shaft 2 leaves the cam surface 30a, the spring 29 swings the latch or pawl 30 back to the position shown in Fig. 4, so that all parts again occupy their normal positions. The zero setting of the result counting register B will then take place upon the next rotation of the shaft 2 unless the handle 26 is again actuated to make the cam 21 inoperative.

The projection bar 20 has also an arm 32 extending in the opposite direction of the arm 31. The arm 32 is, however, not so long and high that it can meet the cam surface 30a on the latch pawl 30.

The arms 31 and 32 of the projection bar 20 extend radially in opposite directions and have their sides remote from the shaft 2 situated in the same plane. In the normal position of the parts, said sides are pressed against a central elevation of the bottom 21a of the cam 21 by the pressure spring 7 inserted between the arms and the toothed wheel 6, as will best be seen from Figs. 7 and 8. At the free end of the arm 32, there is a recess 33 in the edge facing the cam 21, and at the same distance from the shaft 2 the longer arm 31 has a recess 34 in its edge facing the cam. When the cam 21 occupies the inoperative position shown in Figs. 5, 8 and 9, in which position it is coaxial with the shaft 2, the recesses 33 and 34 of the arms 31 and 32 embrace the cam 21 without being actuated by it during the rotation of the shaft 2, so that the spring 7 can hold the arms 31 and 32 and thus the projection bar 20 axially unmovably in engagement with the bottom 21a of the cam whereby no zero setting of the digit wheels 19 of the result counting register B takes place. However, when the cam 21 occupies the operative position shown in Figs. 4, 7 and 10 to 12, in which position the cam is eccentric in relation to the shaft 2 the projection bar 20 is displaced in the manner described below during a single rotation of the shaft 2 by means of the handle 4.

The frontal face of the annular cam 21, facing the shaft 2 is situated in a plane at right angles to the shaft except on two diametrically opposite

places where the cam opposite the arm 31 occupying the normal position has a recess 35 with a steep side wall and an inclined side wall and opposite the arm 32 occupying the normal position has a relatively broad recess 36 with steep side walls. Owing to the eccentric position of the cam 21 in relation to the shaft 2, the active edge of the arm 31 facing the cam engages the recess 35 with its portion outside of the recess 34, and the active edge of the arm 32, facing the cam 21, engages the recess 36 in cam 21. When the shaft 2 begins to perform one revolution for a zero setting operation, the active edge of the arm 31 therefore slides up along the inclined side wall of the recess 35 (Fig. 10), so that the projection bar 20 is displaced in axial direction under compression of the spring 7. During the continued rotation, the active edges of the arms 31 and 32 slide on the main portion of the active end surface of the cam 21, which portion is situated in a plane at right angles to the shaft 2. Owing to the eccentric arrangement of the shaft 2 and the cam 21, the recess 34 of the arm 31 will pass during the rotation directly over the cam 21 in a certain position of rotation of the shaft 2. In this position the projection bar 20 is prevented from being displaced against the bottom 21a of the cam under the action of the spring 7 due to the fact that the active edge of the arm 32 is applied to the main portion of the active end surface of the cam 21, as will be seen from Fig. 11. When the arm 31 passes the recess 36 of the cam, it must be prevented from sinking down into this recess, since in this position, the arm 32 is situated opposite the recess 35 and is within the cam ring because of the eccentric arrangement of the shaft 2 and the cam 21 (see Fig. 12). For this purpose the handle 26 is provided with a portion 26a (see Figs. 4 and 12) one side of which is arranged in the same plane as the main portion of the active end surface of the cam 21 and is situated adjacent the recess 36, so that the active edge of the arm 31 outside the recess 34 slides on the portion 26a while the arm 31 passes the recess 36 in the cam 21. At the end of the single rotation of the shaft 2, the arm 31 drops down into the cam recess 35 along its steep side under the action of the spring 7, whereafter the parts again occupy their normal position, and the digit wheels 19 in the result counting register B are reset to zero.

The invention may, of course be realized in many different ways and the embodiment described above in connection with the annexed drawings must therefore be considered as an example only which has been chosen for the elucidation of the invention. It may especially be pointed out that the shaft 2 common to the two counting registers A and B may be replaced by two separate shafts, one for each counting register. In such an instance, it is possible to arrange the zero setting projections stationarily with regard to the shafts while displacing the shafts in axial direction. In using separate shafts for the different counting registers, the shafts need not be coaxial with regard to each other. They should, however, be in driving connection with each other, so that they may be actuated together by means of a handle or any other driving means. Instead of making the cam 21 movable at right angles to the zero setting shaft, it may, for instance, be made movable in axial direction, although the mechanism will be more complicated and space requiring in such an instance. If desired, both, the revolutions counting register and the result counting register, may be made op-

tionally, zero settable in the manner described for the result counting register. Such a modification is shown in Figure 13, which substantially corresponds to the structure of Figure 1 with the exception that the cam mechanism 16, 17 at the left-hand side of Figure 1 has been replaced by a cam mechanism 21, 31, 32 which is identical to the cam mechanism 21, 34, 32 at the right-hand side of Figure 1 in construction as well as in operation. It is, of course, also possible to zero set more than the two counting registers shown by means of a single drive means. It is further possible to divide a counting register into sections which may be zero set optionally and independently of each other by means of a device according to the invention. In addition to calculating machines and the like machines, such as book-keeping machines, the invention may also be used in other apparatus with one or more counting registers e. g. various registering apparatus and meters.

What we claim and desired to secure by Letters Patent is:

1. In combination in a counting register, a plurality of digit wheel groups, a plurality of sets of zero setting means respectively associated with said digit wheel groups, means normally holding each of said sets in an inoperative position, a handle movable selectively in a predetermined direction for simultaneously revolving each of said sets of zero setting means around the digit wheel axis of the associated digit wheel group, a plurality of arms respectively connected to each of said sets of zero setting means and extending radially with regard to the digit wheel axis of the associated digit wheel group, a plurality of annular cams respectively associated with each of said arms for displacing each of said sets of zero setting means from the inoperative position to an operative position in which the zero setting means will engage the associated digit wheels and rotate them to zero position in response to the movement of said handle in said predetermined direction, and means for optionally moving at least one of said annular cams between an operative position in which said cam is eccentrically positioned with regard to the digit wheel axis of the associated digit wheel group, and an inoperative position in which said cam is concentrically positioned with regard to the digit wheel axis of the associated digit wheel group, said radially extending arm associated with said cam movable between said operative and inoperative positions being provided with recesses arranged so that said last-mentioned movable cam projects into the recesses when in inoperative position.

2. In combination in a counting register, a plurality of digit wheel groups, a plurality of sets of zero setting means respectively associated with said digit wheel groups, means normally holding each of said sets in an inoperative position, a handle movable selectively in a predetermined direction for simultaneously revolving each of said sets of zero setting means around the digit wheel axis of the associated digit wheel group, a plurality of arms respectively connected to each of said sets of zero setting means and extending radially with regard to the digit wheel axis of the associated digit wheel group, a plurality of annular cams respectively associated with each of said arms for displacing each of said sets of zero setting means from the inoperative position to an operative position in which the zero setting means will engage the associated digit wheels and rotate them to zero position in response to the

movement of said handle in said predetermined direction, means for optionally moving at least one of said annular cams between an operative position, in which said cam is eccentrically positioned with regard to the digit wheel axis of the associated digit wheel group, and an inoperative position in which said cam is concentrically positioned with regard to the digit wheel axis of the associated digit wheel group, said radially extending arm associated with said cam movable between said operative and inoperative positions being provided with recesses arranged so that said last-mentioned movable cam projects into the recesses when in inoperative position, spring means tending to hold said movable cam in operative position, and latch means for holding said movable cam in inoperative position against the thrust of said spring means, said latch means being operable at the end of a zero setting operation by said radially extending arm cooperating with said movable cam held by said latch means for releasing said movable cam to permit said spring means to move said movable cam into the operative position.

3. A counting register comprising in combination, a plurality of digit wheel groups, a plurality of sets of zero setting means respectively associated with said digit wheel groups, means normally holding each of said sets in an inoperative position, a handle movable selectively in a predetermined direction for simultaneously revolving each of said sets of zero setting means around the digit wheel axis of the associated digit wheel group, a plurality of arms respectively connected to each of said sets of zero setting means and extending radially with regard to the digit wheel axis of the associated digit wheel group, a plurality of annular cams respectively associated with each of said arms for displacing each of said sets of zero setting means from the inoperative position to an operative position in which the zero setting means will engage the associated digit wheels and rotate them to zero position in response to the movement of said handle in said predetermined direction, means for optionally moving at least one of said annular cams between an operative position, in which said cam is eccentrically positioned with regard to the digit wheel axis of the associated digit wheel group, and an inoperative position in which said cam is concentrically positioned with regard to the digit wheel axis of the associated digit wheel group, said radially extending arm associated with said cam movable between said operative and inoperative positions being provided with recesses arranged so that said last-mentioned movable cam projects into the recesses when in inoperative position, and means arranged for actuation by said radially extending arm and operable automatically at the end of each zero setting operation to bring about movement of said optionally movable cam into its operative position if said last mentioned cam is in its inoperative position.

4. A counting register comprising in combination, a plurality of digit wheel groups, a plurality of sets of zero setting means respectively associated with said digit wheel groups and operable selectively to zero set said digit wheel groups, means associated with said zero setting means and normally holding each of said sets of zero setting means in an ineffective position, a handle movable selectively in a predetermined direction for simultaneously revolving each of said sets of zero setting means around the digit wheel axis

of the associated digit wheel group, arm means respectively connected to said sets of zero setting means, a plurality of cam means respectively associated with each of said arm means, said cam means being movable into an operative position for actuation of said arm means to thereby make said zero setting means effective in response to the movement of said handle in said predetermined direction, spring means operatively connected with and tending to urge said movable cam means into and to hold the same in its operative position, manually operable means associated with and operable to move at least one of said cam means into an inoperative position, locking means operable prior to the movement of said handle in said predetermined direction to lock said movable cam means in its inoperative position against the thrust of said spring means, and means arranged for cooperation with said locking means and operable in response to movement of said handle at the end of a zero setting operation to make said locking means ineffective, thereby allowing said spring means to move said movable cam means into its operative position.

5. In a calculating machine comprising a plurality of digit wheel groups, a plurality of sets of normally ineffective zero setting means respectively associated therewith for zero setting the same, and rotatable actuating means for operating said zero setting means, the combination of arm means respectively connected to said sets of zero setting means, cam means associated with said arm means and normally occupying an effective position so as to cause said arm means to slide along the cam surface of said cam means in response to a first predetermined rotative movement of said actuating means, thereby rendering effective the zero setting means pertaining thereto, manually operable means associated with one of said cam means and operable independently of said actuating means for moving said cam means into ineffective position, thereby preventing actuation of said arm means by said cam means during said first predetermined rotative movement of said actuating means, locking means associated with said one cam means and operable to lock the same in its ineffective position when so adjusted by predetermined movement of said manually operable means, and means operatively connected with said actuating means and responsive to a second predetermined rotative movement thereof for making said locking means ineffective to thereby allow return of said cam means into its operative position.
